UNITED STATES PATENT OFFICE.

CHARLES V. KERR, OF CHICAGO, ILLINOIS.

CONDENSING APPARATUS.

1,159,778.

Specification of Letters Patent.

Patented Nov. 9, 1915.

Application filed May 19, 1915. Serial No. 29,194.

To all whom it may concern:

Be it known that I, CHARLES V. KERR, a citizen of the United States, residing at Chicago, in the county of Cook and State of Illinois, have invented certain new and useful Improvements in Condensing Apparatus, of which the following is a specification.

My invention relates to steam condensing apparatus for engine plants and of the type which I have termed baro-surface condensing.

The objects of my invention are, first, to so arrange and construct the circulating pump, condenser, and air pump, and connect up the same, as to enable the water passing through the condenser, to act and perform the function of withdrawing the air in the condenser which has been liberated from the condensed exhaust steam; second, to so construct, arrange and connect up different elements comprising the system, that a high vacuum is produced in the condenser without the use of a costly and complicated piston air pump, thereby producing a most simple and effective condensing system, requiring a minimum use of water and repairs; third, to construct and arrange the different elements comprising the apparatus so that a condensing plant is produced which is compact, of low first cost, of high and constant efficiency, and in which all the parts are easily assembled or taken apart, quickly inspected or repaired, and kept clean of incrustation; fourth, to so construct and arrange the parts of the air pump, and so connect the same up in the apparatus, that a high vacuum is produced in a surface condenser without the use of a piston air pump operated by steam or other motive fluid; fifth, other objects and advantages of the construction and arrangement of the apparatus will appear from the detailed description of the preferred form, to be hereinafter given.

The invention consists of structural features and relative arrangements of the elements comprising the invention which will be hereinafter more fully described and particularly pointed out in the appended claims.

Referring to the two sheets of drawings, illustrating the preferred form of my invention, in which similar reference characters indicate the same parts in the several figures, Figure 1 is a side elevation of the condensing system; Fig. 2 is a vertical lon-

gitudinal section of the air pump on line II-II of Fig. 3; Fig. 3 is a transverse section of the pump taken on line III-III of Fig. 2; and Fig. 4 is an enlarged side view partly in section showing the relation of the tubes and tube sheets of the air pump.

In the drawings as shown in Fig. 1, the numeral 1 indicates a circulating pump of the centrifugal class, of any approved form, but more especially of the type shown in my co-pending application for patent, Serial No. 786,946 and filed August 27, 1913. The inlet or suction side of said pump 1 is connected by means of the pipe 2 with any suitable cooling water supply 3. Interposed in the pipe 2 between the cooling water supply tank 3 and the suction inlet of the pump 1, is provided a screen box 4 to intercept any impurities or floating material and keep them from passing into the pump 1 and the condenser.

5 is any condenser of the surface type, but preferably of the form shown in my co-pending application Serial No. 796,747, filed Oct. 23, 1913, and is provided with an upper steam inlet 6, a lower condensed steam outlet 7, and a lower air collecting chamber 8, having an outlet 8'. Said condenser 5 is also provided with a lower water inlet 9 and an upper water outlet or discharge 10, said inlet 9 being connected by means of a pipe 11 with the discharge outlet of the pump 1. In said pipe 11 between the inlet 9 of condenser 5 and discharge of the pump 1, is interposed a check valve 12 to prevent the water from running downward in the piping, if the pump 1 is stopped for any reason.

At the top of the condensing apparatus is provided an improved form of "barometric" air pump 13, which may be carried by any suitable supports, not shown, and said pump consists of a casing 14, preferably conical in shape at its lower portion, and cylindrical at its upper portion that forms a lower air suction chamber 15, having a lower lateral air inlet opening 16, connected with a branch pipe 17. (see Fig. 2). The cylindrical or upper portion is provided with an upper opening 18 and the lower portion with a lower opening or discharge 19. The opening 18 is closed by a circular perforated plate 20, through which is inserted, fitted and supported at their upper ends a series of depending tubes 21, preferably of uniform diameter and of such length as to ex-

tend within the lower air suction chamber 15 as shown in Fig. 2. Attached to the upper side or flange of the upper cylindrical portion of the casing 14, and supported over the plate 20, and opening 18 is a cylindrical water chamber section 22, provided with a water inlet opening 23.

Seated upon the upper flange of the cylindrical water chamber 22, is a plate 24, having a series of perforations smaller in diameter than the perforations in the plate 18, but arranged directly over the same. Inserted in the perforations of the plate 24 is a series of depending tubes 25, smaller in diameter than the tubes 21, of plate 20, and whose upper ends are securely fastened to the plate 24, while the body of the tubes 25, pass through the water chamber 22, and their lower ends extend into and near the ends of the tubes 21, as clearly shown in Figs. 2 and 4.

Attached to the upper side and flange of the cylindrical water chamber section 22 is a cap 26, having formed therein an upper air suction chamber 27, provided with an upper air inlet 28, to which is connected a branch air pipe 29 as shown in Fig. 2, and for purposes to be presently described. The water outlet opening 10, of the condenser 5 is connected by a pipe 30, with the water inlet 23, of the air pump 13, and pipe 31, connects the outlet 8', of the air collecting chamber 8, in the condenser 5, by means of the branch pipes 17 and 29, with the lower and upper air suction chambers 15 and 27, respectively, within the air pump 13. The discharge or lower opening 19, of the air pump 13, is connected by a pipe 32, for conveying the water and entrained air to a tail race 33.

The operation of the invention is as follows:—The circulating pump 1 having been primed, is put into operation and as soon as vacuum is formed, exhaust steam is passed through the upper inlet 6 and into the condenser 5. Said pump draws the cooling water from the supply tank 3 up the suction pipe 2 through the screen box 4 and forces said water from the discharge of the pump 50 beyond the check valve 12 through the pipe 11 into the lower water inlet 9 of the surface condenser 5, thence around the outside of tubes of the surface condenser and out of the discharge opening 10 and up and through the pipe 30. The cooling water reaching the upper end of the pipe 30, flows into the inlet 23 of the water chamber 22 of the air pump 13, and is distributed uniformly around the upper tubes 25, and over the perforated plate 20, from whence said water flows into the annular spaces between the lower section of the tubes 25, and the upper ends of the tubes 21 and down through the depending tubes 21. The water 65 within the depending tubes 21 passing the

ends of the inner tubes 25 draws the air out of said tubes 25, and tends to produce a vacuum within the suction chamber 27, which in turn exhausts the air from the air chamber 8 of the condenser 5 by the air passing through the connecting pipes 31 and 29 as will be readily understood. The water discharging from the lower ends of the tubes 21, forms a series of separated water jets which present a large total surface to the air, said jets drawing the air surrounding the tubes 21, and collected in the lower air suction chamber 15, and continually forcing or ejecting the air into the lower section of the conical casing 14 where it becomes entrained with the rapidly descending water falling through the discharge or lower opening 19 into the pipe 32 from which the air and water are conveyed to the tail race 33. As the cooling water 85 continues to flow downwardly through the pipes or tubes 27, a high vacuum is also produced in the air suction chamber 21, and the air liberated from the condensing steam and collected at the bottom of the condenser 90 in the air chamber 8, passes through the opening 8', into the air discharge pipe 31 and is drawn through the inlet 16, by branch pipe 17 into the space surrounding the tubes 21, where said air is constantly and efficiently carried down and out with the discharging water. Thus it will be seen that the same water that is employed to condense the exhaust steam in the condenser is used to evacuate the air from two chambers in 100 the condenser, and hence the air from the condenser is divided and enters the air pump 13 into said suction chambers above and below the water chamber or inlet, and thereby gives double the surface of contact between 105 the water and air than accomplished in prior devices for the same purpose, which construction and arrangement as will be readily seen, avoids the use of the usual costly and complicated piston air pump, and 110 reduces the condensing system of a steam plant to its simplest, compact and most efficient form. Furthermore, as the cooling water is taken from and discharged to the same level, the power required in the circulating pump is only that necessary to overcome the friction in the piping and condenser, and on account of the large cross section of the condenser employed, the frictional resistance is reduced to a minimum. 115 Also in view of the cooling water discharged from the air pump carrying air with it at the temperature of the water, the density of said water is less than normal, and it is found best to arrange the lower end of the air pump 13 formed thereby from thirty to forty feet above the level of the tail race 33, and while somewhat higher than the usual barometric condensers, it is not detrimental 125 in the efficient operation thereof, as the 130

vacuum in the barometric air pump 13 is very high and assists in lifting the water to the height mentioned.

As will be seen from the foregoing detailed description of the system, and its method of operation, all the objects and advantages of the invention recited in the statement of invention are fully and efficiently carried out, and the condenser is capable of maintaining a high vacuum with a minimum consumption of cooling water and coal.

What I claim is:—

1. A condensing apparatus comprising a surface condenser having a water inlet, a water outlet, an exhaust steam inlet, a condensed steam outlet and an air collecting chamber, an air ejecting pump casing having a water chamber provided with a water inlet connected above the barometric height with the water outlet of the condenser, a water outlet connected with a tail race, and an upper and a lower air exhausting chamber, respectively, above and below said water chamber and connected with the air collecting chamber of the condenser, a lower series of tubes within the air pump casing, said lower tubes being so arranged as to have their upper ends in communication with the water chamber and water inlet of the pump casing and their lower ends discharging into the water outlet of the pump casing and in communication with the lower air exhausting chamber of the pump casing, an upper series of tubes within the water chamber of smaller diameter than the lower series of tubes and having the upper ends in communication with the upper air exhausting chamber and their lower ends passing into the upper open ends of the lower series of tubes, and a circulating pump having its inlet connected with a cooling water supply and its discharge connected with the inlet of the surface condenser.

2. A condensing apparatus comprising a surface condenser having a water inlet, a water outlet, an exhaust steam inlet, a condensed steam outlet and an air collecting chamber, an air ejecting pump casing disposed at a higher level than the condenser having a water chamber provided with a water inlet connected above the barometric height with the water outlet of the condenser, a water outlet connected with the tail race, and an upper and a lower air exhausting chamber, respectively, above and below said water chamber and connected with the air collecting chamber of the condenser, a lower series of separated vertical tubes within the air pump casing, said tubes being so arranged as to have their upper ends in communication with the water chamber and water inlet of the pump casing and their lower ends discharging into the water outlet of the pump casing and in

communication with the lower air exhausting chamber of the pump casing, an upper series of tubes within the water chamber of smaller diameter than the lower series of tubes and having the upper ends in communication with the upper air exhausting chamber and their lower ends passing into the upper open ends of the lower series of tubes, and a circulating pump having its inlet connected with a cooling water supply and its discharge connected with the inlet of the surface condenser.

3. A condensing apparatus comprising a surface condenser having a water inlet, a water outlet, an exhaust steam inlet, a condensed steam outlet and an air collecting chamber, an air ejecting pump casing having a water chamber provided with a water inlet connected above the barometric height with the water outlet of the condenser, a water outlet connected with a tail race, and an air exhausting chamber above said water chamber and connected with the air collecting chamber of the condenser, a lower series of tubes within the air pump casing, said lower tubes being so arranged as to have their upper ends in communication with the water chamber and water inlet of the pump casing and their lower end discharging into the water outlet of the pump casing, an upper series of tubes within the water chamber of smaller diameter than the lower series of tubes and having the upper ends in communication with the air exhausting chamber and their lower ends passing into the upper open ends of the lower series of tubes, and a circulating pump having its inlet connected with a cooling water supply and its discharge connected with the inlet of the surface condenser.

4. A condensing apparatus comprising a surface condenser having an air collecting chamber, a circulating pump connected with the condenser, an air ejector pump consisting of a hollow conical casing having a lower annular air exhausting chamber and air inlet at its larger end connected with the condenser, and a water outlet at the smaller end, a water chamber above said conical casing, an air exhausting chamber above the water chamber having an inlet connected with the air collecting chamber of the condenser, a lower series of separated tubes within the conical casing and projecting through the lower air exhausting chamber, said tubes having their upper ends communicating with the water chamber and their lower ends in communication with the lower air chamber and discharging into the outlet of the conical casing, and an upper series of tubes within the water chamber of smaller diameter than the lower series of tubes and having the upper ends in communication with the upper air exhausting chamber and their lower ends passing into

the upper open ends of the lower series of tubes.

5. A condensing apparatus comprising a surface condenser having an air collecting chamber, a circulating pump connected with the condenser, an air ejector pump situated above the condenser and consisting of a hollow conical casing having a lower annular air exhausting chamber and an air inlet at its larger end connected with the condenser, and a water outlet at the smaller or lower end, a water chamber above said conical casing, a lower perforated plate separating the upper end of the conical casing from the water chamber, a series of separated tubes within the conical casing and projecting through the lower air exhausting chamber, said tubes having their upper ends secured in the openings of the lower perforated plate and communicating with the water chamber and water inlet and their lower ends discharging into the water outlet

of the conical casing, an upper air exhausting chamber above the water chamber having an inlet connected with the air collecting chamber of the condenser, an upper perforated plate separating the upper end of the water chamber from the lower end of the upper air exhausting chamber, and an upper series of tubes within the water chamber of smaller diameter than the lower series of tubes and having their upper ends secured in the openings of the upper perforated plate and in communication with the upper air exhausting chamber and their lower ends passing into the upper open ends of the lower series of tubes. 25 30 35

In testimony whereof I affix my signature in presence of two witnesses.
